CLAIM

We claim the ornamental design for a mortar and base assembly, as shown and described.

DESCRIPTION

FIG. 1 is a perspective view of our design for a mortar and base assembly;

FIG. 2 is an elevational view of our design for a mortar and base assembly;

FIG. 3 is a top view of our design for a mortar and base assembly;

FIG. 4 is a bottom view our design for a mortar and base assembly;

FIG. 5 is a perspective view of our design for a mortar portion of a mortar and base assembly;

FIG. 6 is an elevational view of our design for a mortar portion of a mortar and base assembly;

FIG. 7 is a top view of our design for a mortar portion of a mortar and base assembly;

FIG. 8 is a bottom view of our design for a mortar portion of a mortar and base assembly;

FIG. 9 is a perspective view of our design for a base portion of a mortar and base assembly;

FIG. 10 is an elevational view of our design for a base portion of a mortar and base assembly;

FIG. 11 is a top view of our design for a base portion of a mortar and base assembly; and,

FIG. 12 is a bottom view of our design for a base portion of a mortar and base assembly.

1 Claim, 4 Drawing Sheets
